UNITED STATES PATENT OFFICE.

JOHN L. DAWES, OF PITTSBURG, PENNSYLVANIA.

DESIGN FOR AN ILLUMINATED CHANDELIER-SIGN.

No. 37,800.

Specification for Design.

Patented Jan. 30, 1906.

Application filed December 21, 1905. Serial No. 292,868. Term of patent 3½ years.

To all whom it may concern:

Be it known that I, JOHN L. DAWES, of Pittsburgh, Allegheny county, Pennsylvania, have invented a new, original, and ornamental Design for Illuminated Chandelier-Signs, reference being had to the accompanying drawing, forming part of this specification, which is a perspective view of an illuminated chandelier-sign embodying my design.

I claim—

The ornamental design for an illuminated chandelier-sign, as shown.

JOHN L. DAWES.

Witnesses:

H. M. CORWIN,
JOHN MILLER.
